UNITED STATES PATENT OFFICE.

HERBERT L. G. MOORE, OF HOHOKUS, NEW JERSEY.

EGG HOLDER AND CARRIER.

Application filed July 8, 1920. Serial No. 394,752.

To all whom it may concern:

Be it known that I, HERBERT L. G. MOORE, a citizen of the United States, residing at Hohokus, in the county of Bergen and State of New Jersey, have invented an Improvement in Egg Holders and Carriers, of which the following is a specification.

My invention relates to trays or holders for eggs intended for transportation by mail or express, and where a plurality of trays filled with eggs are packed together in a single box or case, such as shown in the patent granted to me August 25, 1914, numbered 1,108,606, in which each tray is composed of two members interlocked to form a plurality of egg receptacles.

When a number of such trays are packed in a case for shipment of eggs, there is a considerable amount of lost space, because it is necessary to invert one empty tray over another filled tray, while the next filled tray is seated upon the upturned bottom of the inverted tray, and so on.

Furthermore while the trays made according to my said patent are strong enough to retain their form when being individually handled while containing one dozen eggs, they are not sufficiently rigid to retain their proper form when being individually handled, if made of a size large enough to contain two dozen eggs.

One object of the present invention is to overcome such difficulty by greatly strengthening the tray; another object is to take up lost space in packing, thereby lessening labor and expense; another object is to provide increased protection for the eggs, and a further object is to allow for the free circulation of air throughout the packed trays.

The details of the invention are herein-after particularly described.

In the accompanying drawings:

Figure 1 is a plan view of one of the three sheets of which my improved tray is formed, showing the same in flat form.

Fig. 2 is an edge view of the same sheet in folded form.

Fig. 3 is a plan of the second sheet in flat form.

Fig. 4 is an edge view of the same sheet folded.

Fig. 5 is a plan view of the third sheet in flat form.

Fig. 6 is an edge view of the same sheet folded.

Fig. 7 is a plan of the tray completed. This figure illustrates the appearance of both sides of the tray, as the tray has the same appearance when reversed.

Fig. 8 is a section on the line 8—8 of Fig. 7 and

Fig. 9 is a sectional elevation showing the manner in which the eggs are packed for transportation.

Similar reference characters denote like parts throughout the several views.

The device may be made of any suitable material, and provides a tray having pockets or egg receptacles on both sides.

In the construction shown I make use of three sheets of material, preferably light cardboard, each scored, cut, folded and all interlocked in such manner as to form a plurality of single egg receptacles both on the top and bottom of the tray, each receptacle having a plurality of converging walls.

Referring to the drawing, the three rectangular sheets of cardboard, or other suitable material, are denoted by the reference numerals 10, 11 and 12, respectively.

These sheets are each scored and cut while in flat form. The sheet 10, is separately illustrated by plan view in Fig. 1.

The surface of this sheet on one side is creased or lightly scored transversely on the lines, *a*, *b*, *c*, *d*, *e*, *f*, *g*, *h*, *i*, *j*, *k*.

Spaced openings 13, approximately X shaped are cut out on the lines *b*, *d*, *f*, *h*, and *j*, each row being in alignment.

Similar openings 14, are cut out on the lines *c*, *e*, *g* and *i*; these parallel rows of openings also being in alignment with each other, but out of alignment with the parallel rows of openings 13, that is, they come between them.

Smaller openings 15, but of approximately the same shape are cut out on the line *a*, and similar openings 16, are cut out on the line *k*; both of these rows of small openings are in alignment with the rows of larger openings 14.

Adjacent the outer longitudinal edges of the sheet and on the lines *b*, *d*, *f*, *h* and *j*, approximately triangular openings 17 are cut out; this sheet is then folded on the scored lines so that it assumes the zig zag shape shown in the side view, Fig. 2.

The sheet 11, is separately illustrated in flat form by plan view in Fig. 3. This sheet is of slightly less width and length than the sheet 10. It is creased or scored 5 transversely on its under surface on the lines *l*, *m*, *n*, *o*, *p* and *q*.

Between these scored lines, parallel and aligned rows of openings 18, are cut out of the shape shown, and at the ends of each row 10 there are cut out openings 19, having straight outer edges with curved inner edges as shown.

The peculiar form of the openings 18 and 15, leaves comparatively narrow strips 20 between the openings at their centers, the function of which will be hereafter described.

This sheet 11 is then folded on the scored 20 lines when it assumes the shape shown in Fig. 4.

The sheet 12, in flat form is shown by plan view in Fig. 5. This sheet is of the same length, but of less width than the sheet 10. It is creased or scored transversely on 25 its upper surface on the parallel lines *r*, *s*, *t*, *u*, *v*, *w*, and *x*.

Between these scored lines, parallel and aligned rows of openings 21, are cut out of the same shape as the openings 18, in sheet 30 11, but instead of having end openings similar to the end openings 19, in sheet 11, this sheet 12, is provided with an additional opening in each row of the larger shape, or in other words it has five openings 21 in 35 each row, instead of four as in sheet 11. Comparatively narrow strips 22, are formed between the openings in sheet 12, similar to the strips 20, in sheet 11, and have the same function.

40 This sheet 12 is then folded on the scored lines when it assumes the shape shown in Fig. 6.

The three sheets 10, 11, and 12, are now 45 ready to be assembled, which is done in the following manner:

The X-shaped openings 14, 15 and 16 in the sheet 10, in its folded form provide vertical slots at the tops of the folds on the lines *a*, *c*, *e*, *g*, *i* and *k* terminating in two diverging slots on the oppositely inclined portions, while the X-shaped openings 13, form similar slots extending upwardly from the bottom folds on the lines *b*, *d*, *f*, *h* and *j*; the triangular openings 17, extending at an upward and inward inclination on the opposite sides of the folds.

The peculiar shape of the openings 18, in the sheet 11, provide inwardly curved projections 23, at opposite sides of each opening. In assembling the folded sheets 10 and 60 11, the sheet 11, is positioned over the sheet 10, with its folds at right angles to the folds in sheet 10; the projections 23, on the sheet 11, are then inserted into the slots formed 65 by the X-shaped openings in the sheet 10, in

its folded form and by pressing downward upon the sheet 11, the opposite projections 23, will follow into the diverging slots in the sheet 10, thus bringing the oppositely disposed V shaped portions 24 of the sheet 11, 70 into position to form two converging walls of each pocket or egg receptacle 25, while that portion of the inclined surface of the sheet 10, between the rows of X shaped openings cut on the lines *a*, *c*, *e*, *g*, *i* and *k* forms 75 the other converging walls of the pockets, the narrow strips 20, connecting the oppositely disposed V-shaped portions 24, forming a flexible bearing for one end of the eggs at the bottom of each pocket. The 80 folded ends 26 and 27 of the sheet 11, are inserted into the smaller X shaped openings 15 and 16, in the sheet 10. When the sheet 11, is pushed down to the full extent of the 85 slots in the sheet 10, the top edges of the folds in both sheets are flush with each other.

The extreme side edges of the sheet 11, project in curved or zig zag form beyond the egg receptacles, as do the extreme ends of the sheet 10.

90 After the sheets 10, and 11, have been assembled in the manner just described, the tray thus far completed is turned over, when the sheet 12, is connected with the sheet 10, in a similar manner to the sheet 11, that is, 95 the curved projections 28, in the openings 21 corresponding with the projections 23 on sheet 11 are inserted into the slots formed by the X shaped openings in the sheet 12, in its folded form; when pushed down the opposite projections 28 will follow into the diverging slots in the sheet 10, thus bringing the oppositely disposed V shaped portions 29, of the sheet 12, into position to form two 100 converging walls of each pocket or egg receptacle on this side of the tray, while that portion of the inclined surface of the sheet 10, between the rows of X shaped openings cut on the lines *b*, *d*, *f*, *h* and *j*, forms the other converging walls of the pockets on 110 this side of the tray; the narrow strips 22, connecting the oppositely disposed V-shaped portions 29, forming a flexible bearing for one end of the eggs at the bottom of each pocket.

115 The folded ends 30, of the sheet 12, are inserted into the slots formed by the triangular openings in the sheet 10, while the sides of the sheet 12, projecting beyond the egg receptacles fit over the curved or zig 120 zag projecting ends of the sheet 11. These projecting ends and sides of the tray present a very efficient protection to the egg receptacles from contact of the sides of the tray with any other object.

125 A very strong division between the egg receptacles on both sides of the tray is provided by my invention which renders it impossible for the egg in one receptacle contacting with an egg in another receptacle, 130

and in consequence of the shape of the pockets, the middle or weakest portion of the eggs are out of contact with the walls of the receptacles.

5 While the egg receptacles on both sides of the tray are in parallel rows, only the inclined corners of the receptacles are adjacent each other on the respective sides of the tray, so that it is impossible for the eggs in the 70 receptacles on one side of the tray contacting with the eggs covered by the receptacles on the other side of the tray.

10 The interlocking of the three sheets in the manner described not only provides a tray 75 having pockets on both sides, but gives great strength to the tray so that it may be handled individually when filled with two dozen eggs without bending or liability of injury to the eggs, while the manner in which the 80 openings are cut in the respective sheets, leaves passages for the free circulation of air when the sheets are assembled.

15 As heretofore stated my present invention relates to trays for the transportation of 85 eggs by mail or express, and while it provides a single tray having egg receptacles on both sides, so that either side may be employed for holding eggs, it is particularly designed for use with a packing case in which 90 20 a plurality of trays filled with eggs are contained, and wherein both sides of the tray 95 are made use of at the same time.

25 Figure 8, of the drawings illustrates the manner of packing the filled trays in a box 100 or case for shipment at a distance.

30 31, denotes the box which is preferably of wood and of a size and shaped to receive a plurality of the trays filled with eggs 32 which are usually shipped in quantities of 105 40 six dozen or more.

35 In packing, a tray is placed in the bottom of the box and the pockets on the upper side of this tray are filled with eggs, which are inserted with one end downward so that 110 45 one end of each egg rests upon the narrow strip 20, connecting the V-shaped portions 24, forming two of the converging sides of each pocket. These strips form flexible supports for the ends of the eggs which readily 115 50 conform to the shape of the egg at the end.

55 Another tray is then placed over the eggs in the bottom tray, the pockets in the under side of the second tray covering the upper half of the eggs in the lower tray, while 120 60 the corresponding narrow strips 22, connecting the V-shaped portions 29, forming two of the converging walls of each pocket on this side of the tray bear upon the upper ends of the eggs in the same manner as do 125 65 the corresponding strips upon the lower ends of the eggs before described. In this manner the eggs have a flexible support at each end, while the middle portions of the eggs are out of contact with the walls of the 130 65 pockets.

The pockets on the upper side of the second tray are then filled with eggs in the same manner as the lower tray when their upper half is covered by another tray in the manner just described, and this operation is 70 repeated until the case is filled. The pockets in the upper side of the top tray are not filled, as this tray acts only as a cover for the eggs in the next tray below.

75 The top of this upper tray comes flush with the upper edge of the case so that when the cover of the box is closed it rests upon the top of this tray and holds it firmly in position. The projecting interlocked zig-zag ends and sides of each tray guard the 80 egg receptacles from contact with the inner side walls of the box.

85 It will be readily seen that trays constructed according to my present invention have many advantages over the tray of my prior 90 patent heretofore referred to.

95 The tray is greatly strengthened thereby increasing the protection to the eggs, and allowing for handling a double quantity at one time. A saving of space equal to the 100 depth of one tray is effected in every two layers of eggs packed for shipment in a case, thereby economizing in labor and expense. Air spaces are formed in each pocket on both sides of the tray allowing a free circulation of air throughout the packed trays.

I claim as my invention:

1. An egg-tray composed of three sheets of flexible material, each creased or lightly scored transversely on predetermined 100 spaced parallel lines for the purpose of folding, one of said sheets being provided with approximately X-shaped openings cut out on said scored lines, the other sheets being provided with openings of a shape to enable the three sheets to be interlocked when folded, thereby forming a plurality of 105 single egg receptacles on both sides of the tray.

110 2. An egg-tray composed of three sheets of flexible material, each creased on predetermined spaced parallel lines transversely of the sheet for the purpose of folding, one of said sheets being provided with approximately X-shaped openings cut out on said creased lines, the other sheets being provided with openings of a shape to allow 115 their interlocking with said first sheet when folded, thereby forming a plurality of single egg receptacles on both sides of the 120 tray, each receptacle having four converging walls.

125 3. An egg-tray composed of a plurality of sheets of flexible material, each creased or scored transversely on spaced parallel lines for the purpose of folding, one of said sheets being provided with approximately X-shaped openings cut out on said scored lines, the other sheets being provided with openings of a shape whereby they may interlock with 130

the said first sheet forming a plurality of single egg receptacles on both sides of the tray in such manner that the walls of the respective receptacles do not contact on either side of the tray.

4. An egg tray having a plurality of egg receptacles each receptacle having four converging walls, two of said walls in each receptacle being connected at the bottom by 10 a narrowed portion forming a flexible bearing for the end of an egg and providing an air space at each side thereof.

5. An egg tray having a plurality of egg receptacles on both sides, each receptacle 15 having four converging walls, two of said walls in each receptacle, being connected at the bottom by a narrowed portion forming a flexible bearing for the end of an egg and providing an air space at each side thereof.

20 6. An egg tray having a plurality of egg receptacles on each side, each receptacle having a plurality of converging walls, two of said walls in each receptacle being connected at the bottom by a narrowed portion forming 25 a flexible bearing for one end of the egg, and providing an air space at each side thereof, the receptacles being so arranged with respect to each other that their walls are out of contact on both sides of the tray.

30 7. An egg tray composed of a plurality of sheets of flexible material, one of said sheets being provided with approximately X-shaped openings, the other sheets being provided with openings of a shape whereby 35 they may interlock with the said first sheet, forming a plurality of single egg receptacles on both sides of the tray, each receptacle having a plurality of converging walls, two of which in each receptacle being narrowed

at the bottom providing a flexible bearing 40 for one end of an egg, and leaving an air space at each side thereof.

8. An egg tray composed of three sheets of flexible material, each creased or lightly scored transversely on predetermined spaced 45 parallel lines for the purpose of folding, one of said sheets being provided with approximately X-shaped openings cut out on said scored lines, the other sheets being provided with openings of a shape to enable the three 50 sheets to be interlocked when folded, thereby forming a plurality of single egg receptacles on both sides of the tray, each receptacle having a plurality of converging walls, two of which in each receptacle being narrowed 55 at the bottom, forming a flexible bearing for the end of an egg, and providing an air space at each side thereof.

9. In combination with a packing case, a plurality of egg trays, each composed of a 60 plurality of sheets of flexible material, one of said sheets being provided with approximately X-shaped openings, the other sheets being provided with openings of a shape whereby 65 they may interlock with said first sheet, forming a plurality of single egg receptacles on both sides of the tray, each receptacle having a plurality of converging walls, two of which in each receptacle being narrowed at the bottom providing a resilient 70 bearing for one end of an egg, and leaving an air space at each side thereof, the receptacles on one tray covering the upper half 75 of the eggs in the receptacle on the upper side of the tray beneath when packed for shipment.

Signed by me this 1st day of July, 1920.
HERBERT L. G. MOORE.
